FLEXIBLE GRIPPER MEMBER FOR NEEDLE LOOMS

Johann Gabler, deceased, late of Ettlingen, Germany, by Sophie Gabler, sole heir, Ettlingen, Germany, assignor to F. C. Huyck & Sons, Rensselaer, N. Y., a corporation of New York

Application May 16, 1938, Serial No. 208,302

7 Claims. (Cl. 139—123)

This invention pertains to that type of weaving apparatus known as a "needle loom." In this type of looms the weft thread is inserted by means of grippers moving toward and from each other, 5 and operating to transfer the weft thread from one to the other, in the shape of a loop at a position adjacent the middle of the shed. This method of weft insertion requires that the weft threads should be always as nearly as possible of 10 equal length, so that after the insertion is completed the ends of the weft threads do not materially project beyond the outer warp threads and hence beyond the actual selvage. Equally long weft threads at the insertion are obtained, 15 however, only when every kind of play in the actual inserting mechanism is reduced to a minimum. In narrow looms this is sufficiently obtained by using tappets which are so shaped that the insertion into the shed of the rigid gripper 20 is so timed as to occur at the desired moment. The same applies to the moment of the transfer of the weft thread and the moment at which the gripper leaves the shed. In wide looms this insertion mechanism cannot be used, because operating mechanism for the rigid grippers employed for the insertion of the weft thread would 25 require an exceedingly large increase of the total width of the space required for the loom, which at every increase in the width of the web would amount to twice the extent of this increase. Also, 30 the use of tappets for such widely extending motions of the grippers would lead to insuperable complications, making the employment of this mechanism impracticable.

35 One of the objects of the present invention is to provide means for practical operation of looms of the type mentioned but so constructed and arranged as to avoid the necessity of excessive loom width, by substituting band grippers for the usual 40 form of gripper arms now in general use. A further object is to provide simple and effective means for actuating the band grippers, said actuating mechanism being operable within a minimum space.

45 The invention will be hereinafter fully set forth and particularly pointed out in the claims.

In the accompanying drawing—

Figure 1 is a side elevation, partly in section and with parts broken away illustrating a loom 50 with band gripper mechanism constructed in accordance with the invention. Figure 2 is a front view with parts shown in section.

Referring to the drawing, 10 indicates the slay or reed having arms 11 secured to a rock shaft 12 mounted in the frame 13. Inasmuch as it is

unnecessary to illustrate the entire loom, only one of said arms 11 is shown, it being understood that the slay or reed is of any desired or usual construction well known in the art.

Mounted on the slay or reed 10 is a shaft 14 which movably supports a guide block 15, through which extends the rack portion 16 on a rod 17, the lower end of which is connected to a crank arm 18 mounted on a shaft 19 rotatably supported in the loom frame 20. The shaft 19 is rotated by power applied to a pinion 21 driven by suitable gearing including gears 22 and 23. As shown, the shaft 14 is mounted in suitable bearing arms 25 carried by the slay or reed.

Mounted on said shaft 14, so as to rotate therewith is a pinion 27 meshing with the rack 16. Said shaft 14 also carries a beveled pinion 28 which meshes with a complementary bevel pinion 29 carried by a stub shaft 30 supported by a bracket 29 carried by the slay 10. The shafts 14 and 30 are supported independently of each other with their axes in approximately right angular relation. Said stub shaft also carries a circular driving disk 31.

Secured at one end of a flexible metal band 32 is a weft-thread-gripper device 33, the other end of said band being secured to the periphery of the disk 31. The device 33 may be in the form required to introduce the weft thread into the shed, or of the form to receive the said thread from the weft introducing device and to carry it on through the shed. Said band 32 possesses sufficient stiffness to move the gripper into and out of the shed. Also mounted on the stub shaft 30 is a cover 34 having a peripheral flange 35 35 extended over and encircling the periphery of the disk 31.

In operation, with the various parts of the loom moving in the normal way, vertical reciprocal motion is imparted to the rod 17, 40 thereby imparting oscillations to the pinion 21, and through said pinion and the interposed gearing corresponding oscillations are imparted to the disk 31, thereby moving the gripper member 33 back and forth by reason of the movements of 45 said disk. The gearing is so proportioned that the movements of the crank arm 18 are timed to provide the necessary accuracy of the in and out movements of the gripper member. As the crank arm moves rod 17 up and down, the slay or reed 50 11 will move on its pivot in one direction or the other, according to the immediate direction of movement of the rod 17, and the guide block 14 is so pivoted to the slay or reed that the disk and its operating parts are free to operate irrespec- 55

tive of the change of angle of the rod 17 with respect to the angle of the slay.

The advantages of the invention will be readily understood by those skilled in the art to which it belongs. For instance, it will be observed that by using the bands 32 instead of the old type of rigid arm now in common use, it is possible to operate the gripper by means of mechanism which requires a much narrower space as compared to that necessary where the old type gripper arm is used. By providing a disk around which the flexible member is brought, the gripper member may be reciprocated in a simple manner by mechanism which avoids complications, and a very effective operating device is provided.

Having thus explained the nature of the invention and described an operative manner of constructing and using the same, although without attempting to set forth all of the forms in which it may be made, or all of the forms of its use, what is claimed is:

1. The combination with a pivotally supported slay, of a flexible gripper member so supported by the slay as to be movable into and out of the shed during weaving operations, said flexible member having a thread engaging portion, a guide member pivotally supported by said slay and movable therewith, an operating member mounted to reciprocate through said guide member, means for actuating said operating member, and means associated with said operating member and movable with the slay for imparting reciprocative movements to said flexible member.

2. The combination with a pivotally supported slay, of a flexible member so supported by the slay as to be movable into and out of the shed during weaving operations, said flexible member having a thread engaging portion, a shaft rotatively supported by and movable with said slay, a guide member pivotally mounted upon said shaft, an operating member mounted to reciprocate through said guide member, means for actuating said operating member, means operated by movement of said operating member to impart rotative movements to said shaft, and means associated with said shaft for imparting reciprocative movements to said flexible member.

3. The combination with a pivotally supported slay, of a flexible member so supported by the slay as to be movable into and out of the shed during weaving operations, said flexible member having a thread engaging portion, a shaft rotatively supported by and movable with said slay, a guide member pivotally supported by said shaft, a pinion secured to and rotative with said shaft, a rack member mounted to reciprocate through said guide member and engaging said pinion, and means for actuating said operating member, and means associated with said shaft and movable with said slay for imparting reciprocative movements to the flexible member.

4. The combination with a pivotally supported slay, of a flexible member so supported by the slay as to be movable into and out of the shed during weaving operations, said flexible member

having a thread engaging portion, a disk rotatively supported by and movable with said slay and connected with one end of said flexible member, a guide member pivotally supported by said slay and movable therewith, an operating member mounted to reciprocate through said guide member, means for actuating said operating member, and means associated with said operating member and movable with said slay for imparting rotative movements to said disk.

5. The combination with a pivotally supported slay, of a flexible member so supported by the slay as to be movable into and out of the shed during weaving operations, said flexible member having a thread engaging portion, a disk rotatively supported by and movable with said slay and connected with said flexible member, a shaft rotatively mounted in and movable with said slay, a guide member pivotally supported by said shaft, an operating member mounted to reciprocate through said guide member, means for operating said guide member, means associated with said operating member for imparting rotative movements to said shaft, and means operated by rotative movements of said shaft for imparting corresponding movements to said disk.

6. The combination with a pivotally supported slay, of a flexible member so supported by the slay as to be movable into and out of the shed during weaving operations, said flexible member having a thread engaging portion, a stub shaft supported by and movable with said slay, a disk mounted on said stub shaft and connected with one end of said flexible member, a second shaft rotatively supported by and movable with said slay with its axes disposed at an angle to the axes of the first mentioned shaft, a guide member pivotally supported by the second shaft, an operating member mounted to reciprocate through said guide member, means for actuating said operating member, means associated with the actuator member for rotating the second shaft, and means operated by said second shaft for imparting rotative movements to said disk.

7. The combination with a pivotally supported slay, of a bracket supported by and movable therewith, a flexible gripper member so supported by the slay as to be movable into and out of the shed during weaving operations, said flexible member having a thread engaging portion, a shaft rotatively supported by and movable with said slay, a guide member pivotally supported by said shaft, a rack member mounted to reciprocate through said guide member, a pinion on said shaft engaging said rack member, a stub shaft carried by said bracket, a disk rotatively supported by said stub shaft and connected with one end of said flexible member, means for reciprocating said rack member, and gearing connecting the first mentioned shaft with said disk in such manner that rotative movements are imparted to the disk by rotative movements of said first mentioned shaft.

SOPHIE GABLER,
Sole Heir of Johann Gabler, Deceased.
